INVENTOR:

George A. Holmes,
By Robert Roberts & Holmes,
his attorney.

UNITED STATES PATENT OFFICE.

GEORGE A. HOLMES, OF NEWTON CENTER, MASSACHUSETTS, ASSIGNOR TO UNITED STATES FASTENER COMPANY, OF BOSTON, MASSACHUSETTS, A CORPORATION OF MAINE.

SNAP-FASTENER.

No. 918,325.

Specification of Letters Patent. Patented April 18, 1909.

Application filed July 20, 1908. Serial No. 444,315.

To all whom it may concern:

Be it known that I, GEORGE A. HOLMES, a citizen of the United States, and resident of Newton Center, in the county of Middlesex and State of Massachusetts, have invented 5 new and useful Improvements in Snap-Fasteners, of which the following is a specification.

My invention relates to snap fasteners and 10 more particularly to that class of fasteners which are attached without previous perforation of the material and commonly called "self piercing" fasteners. Its object is to provide a strong and efficient fastener of the 15 kind described which may be quickly and easily secured to the material.

Referring to the drawings, which illustrate an embodiment of my invention, Figures 1 and 2 are respectively sectional views of the 20 upper and lower portions of a socket member, and Figs. 3 and 7 show said portions after they have been assembled. Figs. 4 and 5 are modifications of the upper portion of the 25 socket member shown in Fig. 1, and Fig. 6 shows the modified form of Fig. 5 after the parts of the fastener have been assembled.

A is the upper section of a socket member comprising a female gripping and shearing piece a' having an opening a^2 . A cap a^3 is 30 clenched over said gripping and shearing piece.

B is the lower section of a socket member adapted to be seated on the opposite side of material and comprises a socket chamber b' having a flange b^2 and a male shearing and attaching projection b^3 provided with an inset b^4 .

In securing the socket member the unperforated material is placed between the parts 40 A and B. When pressure is applied by suitable instruments, two results follow. First the material is forced by the projection b^3 against the comparatively sharp edge of the opening a^2 and is sheared so that the projection b^3 passes through the material into the opening a^2 carrying with it the small cut out portion of the material c' . At the same time the edge of the opening a^2 is brought into contact with the inset b^4 . The continuation 45 of pressure forces the piece a' upward toward

the cap causing the edge of the opening a^2 firmly to grip the projection b^3 at the inset b^4 , so that the parts A and B are securely fastened together with the material between them as shown in Fig. 3. 55

Some materials upon which fasteners of this class are used have a tendency to draw away from the fastener, and with such material it is desirable that the fabric shall be very tightly held between the parts A and B. 60 For materials of this kind the shearing and gripping piece a' may be curved, as shown in Fig. 4, or a collet C may be used to aid in gripping the material, as shown in Figs. 5 and 6. 65

The shearing edge of the female member is substantially flush with the lower edge of said female member, so that shearing takes place in the plane of the material and prevents puckering. Were the material first drawn 70 up into the cap before being sheared, puckering would result.

When the fastener is used upon thin material which tends to pull away after the parts have been assembled, it is desirable to 75 form the shearing piece a' as shown in Fig. 4, or to employ a collet C as shown in Figs. 5 and 6.

What I claim and desire to secure by Letters Patent is:— 80

1. A socket member of a snap fastener comprising two parts, one a male member provided with a socket chamber and a male shearing piece at its top, the other a female member adapted to be disposed on the opposite side of material and having a female shearing piece substantially flush with its lower edge, said male member adapted to coöperate with said female member to shear said material and to pass through said material into said female member and to be securely gripped thereby. 85

2. A socket member of a snap fastener comprising two parts, one a male member provided with an inset, a flanged socket chamber and a male shearing piece at its top, the other a capped female member adapted to be disposed on the opposite side of material and provided with an opening, the edge of said opening being substantially 90 95 100

flush with the lower edge of said female member, said male member adapted to co-operate with said female member to shear said material and to pass through said material into said opening and to be securely gripped by said female member with the edge of said opening locked within said inset.

Signed by me at Boston, county of Suffolk, State of Massachusetts this sixth day of July 1908.

GEORGE A. HOLMES.
